UNITED STATES PATENT OFFICE.

JOSEPH SONK, OF PITTSBURGH, PENNSYLVANIA, ASSIGNOR OF ONE-THIRD TO EMIL LIPKA, OF PITTSBURGH, PENNSYLVANIA.

COMBINED KITCHEN-CABINET AND TABLE.

1,161,079.

Specification of Letters Patent. Patented Nov. 23, 1915.

Application filed October 30, 1913, Serial No. 798,307. Renewed September 11, 1915. Serial No. 50,272.

To all whom it may concern:

Be it known that I, JOSEPH SONK, a subject of the Emperor of Austria-Hungary, residing at Pittsburgh, in the county of 5 Allegheny and State of Pennsylvania, have invented certain new and useful Improvements in Combined Kitchen-Cabinets and Tables, of which the following is a specification, reference being had therein to the accompanying drawing.

This invention relates to a combined kitchen cabinet, and has for its object to provide an article of furniture of such class including a plurality of extensible elements 15 connected with a stationary element and adapted when extended to provide a table for dining or for other purposes.

A further object of the invention is to provide in the manner as hereinafter set 20 forth an article of furniture embodying means for storing various articles and further embodying means capable of being extended to constitute a dining table.

Further objects of the invention are to 25 provide a combined table and kitchen cabinet, which is comparatively simple in its construction and arrangement, strong, durable, efficient and convenient in its use, occupying when closed a comparatively small 30 space, readily set up and comparatively inexpensive to manufacture.

With the foregoing and other objects in view, the invention consists of the novel construction, combination and arrangement of 35 parts, as hereinafter more specifically described and illustrated in the accompanying drawings, wherein is shown an embodiment of the invention, but it is to be understood that changes, variations and modifications 40 can be resorted to which come within the scope of the claims hereunto appended.

In the drawings wherein like reference characters denote the corresponding parts throughout the several views, Figure 1 is 45 a front elevation of a combined kitchen cabinet and table in accordance with this invention and illustrated in closed position, Fig. 2 is a vertical sectional view on line Z—Z Fig. 1, Fig. 3 is a sectional plan on line X—X 50 Fig. 1, Fig. 4 is a sectional plan on line Y—Y Fig. 2, Fig. 5 is a longitudinal sectional view illustrating the shiftable elements extended to provide a table, and Fig. 6 is a top plan view of the article when extended to provide the table.

Referring to the drawings in detail, 7 denotes a back, 8 and 9 sides which are secured to the back and each of which has their lower portions 10 of greater width than their upper portions thereby providing a shoulder 11.

The reference character 12 denotes a bottom plate which is of materially less width than the portions 10 of the sides and the said bottom plate 12 is secured to the back 65 7 and the sides 8 and 9.

Mounted upon the shoulders 11 is a platform 13, which projects from the portions 10 of the side walls 8, 9 and abuts against a vertically disposed partition plate 14, 70 which normally abuts against the sides 8, 9 and provides a compartment 15 and a chamber which is divided by the shelves 16 into a plurality of compartments 17. Mounted upon and secured to the platform 13 and 75 also secured to the shelves 16 and to a spacing member 18 is a front frame 19 hinged at one side, as at 20, to the wall 9. Hinged to the front frame, as at 21, is a pair of oppositely disposed doors 22, which when 80 closed are connected together by latches 23. The elements 13 to 23 both inclusive provide what may be termed a hinged receptacle which is capable of being swung outwardly with respect to the walls 8, 9. The 85 compartments 17 of the receptacle are adapted to have any kitchen articles or other devices arranged therein.

Projecting forwardly from the back 7, as well as being secured thereto and to the tops 90 of the walls 8, 9 is a top plate 24 between which and the shoulders 11 is adapted to be positioned the receptacle just referred to. The top plate 24 has connected thereto a vertically disposed top piece 25 for ornamental 95 purposes.

Arranged within the lower portion of the chamber 15, are vertically disposed uprights 27 to each of which is pivotally connected, as at 28, the inner pair 29 of a series of pairs 100 of levers 30, 31 and 32 forming a lazy tongs. The levers of the pairs 30, 31 are pivotally connected together as at 33, the levers of the pair 31 are pivotally connected to the levers of the pair 30, as at 34, and the levers of the pair 31 are pivotally connected to the levers of the pair 32, as at 35, and the levers of the pair 30 are pivotally connected to the levers of the pair 29, as at 36. The lazy tongs which are pivotally connected to one upright 110

27 oppose the lazy tongs pivotally connected to the other upright 27.

Connected to the upper pivots 35, is a table leaf 37, connected to the upper pivots 34 is a table leaf 38, and connected to the upper pivots 36 is a table leaf 39, the opposing edges of the table leaves 37, 38 and 39 are beveled so that when the lazy tongs are extended, the table leaves will snugly fit as illustrated in Fig. 5. When the lazy tongs are folded, the table leaves 37, 38 and 39 will be positioned in parallel relation and extend vertically of the upper portion of the compartment 15, as clearly illustrated in Fig. 3. Normally arranged between the enlarged portions 10 of the side walls 8, 9 is a portable casing 40 provided with rollers 41, and the said casing 40 is pivotally connected by the pivots 42 to the sides of the casing 40. When the casing 40 is positioned between the enlarged lower portions of the side walls 8, 9, it is suspended above the floor by the lazy tongs, as clearly illustrated in Fig. 2. The casing 40, when extended provides a support for the table leaf 37, as illustrated in Fig. 5.

The casing 40 includes an enlarged front 43 which when the casing 40 is positioned between the side walls 8, 9 abuts against the forward edge of the enlarged portions 10 and rests upon a shoulder 44, Figs. 1, 2 and 5. This closes the lower portion of the cabinet. The front plate 43, is provided with handles 45, so that it can be conveniently shifted to extend the lazy tongs to provide the table. The casing 40 is formed with a plurality of drawers 46 having knobs 47.

Copies of this patent may be obtained for five cents each, by addressing the "Commissioner of Patents, Washington, D. C."

What I claim is:—

1. In a combined table and kitchen cabinet comprising a supporting stationary element, a hinged receptacle carried thereby and being capable of swinging outwardly therefrom, a portable casing normally arranged in said element, vertically disposed table leaves normally positioned at the rear of said receptacle and arranged in parallel relation, and a lazy tongs connected with said element and casing and rigidly connected to said leaves for moving said leaves from vertical to horizontal position to provide a table when the casing is pulled outwardly from said element.

2. A combined table and kitchen cabinet comprising stationary supporting element, a hinged receptacle carried thereby and adapted to be swung outwardly therefrom, a portable casing arranged in said element, vertically disposed table leaves normally positioned at the rear of said receptacle and arranged in parallel relation, lazy tongs connected with said element and casing and at its alternate links to said leaves for shifting said leaves from vertical to horizontal position to provide a table when the casing is pulled outward from said element and means for supporting said casing above the floor when the casing is positioned within said element.

In testimony whereof I affix my signature in the presence of two witnesses.

JOSEPH SONK.
